UNITED STATES PATENT OFFICE.

CASS CHAPMAN, OF CHICAGO, ILLINOIS.

AUTOMATIC HATCH, &c.

SPECIFICATION forming part of Letters Patent No. 289,068, dated November 27, 1883.

Application filed March 26, 1883. (No model.)

To all whom it may concern:

Be it known that I, CASS CHAPMAN, of Chicago, Cook county, in the State of Illinois, have invented new and useful improvements 5 in automatic hatches adapted to close the hatchways of elevators, automatically opening to permit the elevator to pass, and closing again after it has passed; and I do hereby declare that the following is an accurate description of the same.

I am aware that hatchways have heretofore been automatically opened and closed by shutters which turn upon hinges or slide bodily in a lateral direction, and therefore I do not 15 broadly claim an automatic shutter for such purposes. The shutters alluded to above are all objectionable, because they are either too much exposed to accidental derangement or injury or weaken the floor too much.

20 These defects are obviated by my invention, which consists, essentially, in a shutter capable of winding around a shaft or reel, and thus capable of being operated and concealed in a very small space beneath the floor, and without 25 weakening any part of the structure.

It also consists in the devices hereinafter described, or their equivalent, for operating my winding-shutter.

That others may fully understand my improvement, I will particularly describe it, having reference to the accompanying drawings, wherein—

Figure 1 is a perspective section of the same. Fig. 2 is a plan of one part of the shutter. Fig. 3 is a vertical section of the same. Figs. 4, 5, 35 6, 7 are details. Fig. 8 is a diagram showing mode of operation. Figs. 9, 10, 11, 12 are details.

A is an ordinary guide-post, of which there 40 is one on each of two opposite sides of the hatchway. On the edge of each post A, fronting the hatchway, there is a guide-strip, b, on which the elevator-car travels in its movements up and down.

45 C is the flooring surrounding the hatchway.

As the devices herein described will be substantially duplicated at each floor, it will only be required to represent those at one floor.

At proper points between the joists and beneath the floor C, on each of the opposite sides

of the hatchway, there is a shaft, D, capable of revolution on its axis.

E E is the shutter, made in two sections, each composed of strips of suitable material joined at their edges, so as to constitute parts or links 55 of a chain capable of being rolled and wrapped around the shaft D. When the elevator-car F is above or below the floor C, the shutters E E are unrolled and drawn across the hatchway, as shown in Fig. 3. Assaid car approaches 60 said shutter either in its ascent or descent, the shutters are pushed back, the shaft D being rotated to roll the shutters around it, so as to withdraw the shutters and leave the hatchway open. When the car has passed, the shutter 65 is again drawn out and the hatchway closed.

It is evident the automatic movement of the shutter E and its shaft D, as described, may be accomplished in a variety of ways, as by means of weights, pulleys, or springs applied 70 directly to the rotating shafts, &c.; but I prefer the simpler mode of pressure applied directly to the edge of the shutter, as hereinafter particularly described. Therefore, without intending to confine myself strictly to the 75 details of construction shown, I will describe the devices as I at present prefer to make them.

The shaft D is made square in cross-section, and the strips which constitute the shutter E are graduated in width, so that as said shaft 80 is rotated the shutter will be wrapped around it, as shown. The combined widths of the shutter-strips on each side are sufficient to reach the guide-strip b, so that when the two shutters are drawn out they will meet at the 85 center of said strip, and thus completely close the hatchway. The shutter-strips are hinged to each other at their adjacent lower edges, and their ends are supported by and travel in suitable grooves made in the side frame of the 90 hatchway. The motive device for each shutter is a chain or flexible strip, which is arranged to engage the car in its ascent and descent, so as to first push the shutter back into its cell, compelling it to rotate the shaft D and 95 wind itself thereon; and, second, after the car has passed to draw said shutter out again and reclose the hatchway. I prefer a chain for this purpose, although it will be manifest that a continuous strip of some suitable flexible ma- 100

terial will accomplish the same purpose. I have therefore shown both forms as modifications in the same plan, but with preference for the chain G. Said chain is constructed with 5 links, each of which is composed of two parallel flat plates, d d, e e, set edgewise, with pivot-bolts f inserted, and between the said plates a carrying-roller, g, so that in operating the shutter there is no dragging friction 10 of the chain in its guideway. As I propose to retract the shutter by pushing against it, instead of by power applied directly to the shaft D, it is desirable that the chain shall have only a limited degree of flexibility, so that it 15 cannot cramp one link with another if the guideway happen to be a little wider than necessary, and also so that when flexed a certain degree it will become like a rigid curved bar. This may be accomplished by stops ar- 20 ranged in a variety of ways; but I prefer to prolong the link-plates e e and make notches h in their ends, as shown, and these, with the cross-pins i, form strong stops without in any way increasing the external dimensions of 25 the chain. The chain G is at one end jointed to the inner or near edge of the outermost strip composing the shutter, and its length is such that when said shutter is entirely re-tracted and the hatchway is open the other 30 end of said chain will exactly reach to the center of the groove k, made in the guide-post A by the side of the guide-strip b. A sliding bar, H, which, for convenience, I will call a "shuttle," slides up and down in said groove, and 35 the end of the chain G is jointed to it at l, so as to be drawn up or down with it, and thereby draw out or retract the shutter. To control and guide the chain as it is drawn out or pushed in by the movement of the shuttle, I 40 place a frog, I, at the point where the groove k intersects the shutter-groove. The frog I is preferably made of cast-iron, and is provided with curved flanges m n, which serve as guide-ways for the chain G, which, as its movement 45 is changed from horizontal to vertical, groove k crosses the frog I centrally. When the car F is below the shutter E, the shuttle will always be at the lower end of its groove k, and when said car is above the shutter said shut- 50 tle will always be at the upper end of said groove, so that from whichever side the car approaches it may engage the shuttle and cause it to push the shutter open, and after the car has passed, by drawing the shuttle to the op- 55 posite end of the groove k, it will cause the shutter to be again drawn out and the hatch-way closed.

It will appear evident to any mechanician that the required engagements and disengagements 60 between the shuttle and car may be secured automatically in a variety of ways. The way I prefer, however, has been selected because it is simple and effective. The shuttle has been provided with notches p q, one near each 65 end, and the car F is correspondingly provided near its upper and lower ends with spring-

latches v s, and each of said latches is provided with a laterally-projecting stud or pin, t, one projecting in one direction and one projecting in the opposite direction. There are also 70 two sets of riding-plates, u u', v v', attached to the guide-post at proper points, so that at the proper moment for disengagement the pin t will ride on its appropriate plate, and the latch will thereby be withdrawn from the notch in 75 75 the shuttle.

In Fig. 8 riding-plates u are shown in full lines and the plates v' in dotted lines. The shuttle is also shown in said figure in its three positions of rest, marked 1, 2, 3. Supposing the car to be in motion upward, the latch will ride over the plate u and will engage with the first shuttle-plate, p, and pushing the shuttle along its groove, the shutter will be opened. At the moment when said shutter has been 85 fully opened the pin t will encounter the riding-plate u' and the cover will be disengaged from the shuttle. A similar riding-plate will prevent engagement of the latch r with the notch q; or the riding-plate u' may be suffi- 90 ciently long for that purpose. The car then passes through the hatchway, and the latch s, having passed over the riding-plate v', will engage with the notch q and draw the shuttle upward until the shutter has been closed, when 95 it will be disengaged in a similar way by the riding-plate v'. These devices and effects are repeated at each floor.

Elevators are frequently placed in a corner of the building, where there is not space for a 100 rolling-up shaft between the hatchway and the wall. In such cases I arrange the pocket w next the wall, and the flexible hatchway-closer runs in and out over the edge of said pocket, a roller being placed at the entrance of said 105 pocket to reduce friction.

By an arrangement of independent riding- 110 plates or equivalent devices, arranged to go into operation upon the breaking of the lift-ing-cable, the descent of the car in falling may be arrested by the first shutter below the point where the breaking occurred, because said independent riding-plates will prevent engagement with the shuttle; but I think it will not be necessary to provide such independent de- 115 vices, because the velocity of the car in falling will probably be sufficient to carry the latches over the shuttle-notch without engagement.

Having described my invention, what I claim 120 as new is—

1. An automatic hatchway-closing shutter, composed of strips of suitable material jointed together along their edges, and adapted to be housed by wrapping around a rotating shaft, 125 combined with elevator car or lift and means whereby motion is communicated from said car to said shutter, substantially as set forth.
2. A hatchway-closing shutter, E, in two parts, composed of some suitable material, 130 jointed together along their lower proximate edges, winding-shafts the revolution of which

extends or retracts said shutter, and a moving or lift and self attaching and detaching means, whereby motion may be transmitted from said car to said winding-shaft.

5. 3. A hatchway-closing shutter, E, composed of strips of suitable material jointed together along their lower proximate edges, and graduated in width as set forth, a square shaft, D, adapted to wrap said shutter around it by its 10 revolution, a moving car and its self attaching and detaching means, whereby the motion of said car may be transmitted through said shutter to said shaft, and the same be caused to rotate by pushing or pulling upon the shutter, 15 as set forth.

4. A wind-up hatchway-closing shutter, E, provided with a shuttle, H, moving in a guideway, k, and a flexible connection between said shuttle and the wind-up shaft of said shutter, 20 and a frog, I, having curved guide-flanges m n, whereby the motion of said shuttle in its groove, above or below its median position, will draw out or retract the shutter, as set forth.

5. A wind-up shutter, E, provided with a 25 shuttle, H, moving in a guideway, k, and a connecting-chain, G, provided with riding-rollers g, and a frog, I, provided with curved guide-flanges m n, whereby the shutter may be drawn out by a movement of said shuttle 30 from its median position toward either end of its slots, and retracted or wound up by movement from either end of said slot toward its median position.

6. A wind-up shutter, E, a shuttle, H, and 35 a frog, I, substantially as set forth, combined with a chain, G, provided with stops whereby its flexibility is limited, as and for the purpose set forth.

7. The chain G, composed of links d d e e, jointed by bolts f, and provided with extended 40 ends and notches h, and the stop-pins i, whereby the flexibility of the chain is limited, and pressure in a vertical direction may be transmitted to a horizontal moving body without support for said chain at the point of deviation. 45

8. The roll-up shutter E, chain G, and shuttle H, provided with notches p q, combined with car F, provided with automatic means to cause engagement and disengagement with said shuttle at the proper times, substantially as set forth. 50

9. A moving elevator lift or car and a hatchway-closing shutter, combined with means whereby said moving car causes said shutter 55 to be positively opened in advance of said car, and again positively closed after the passage of the same.

10. A shutter-operating shuttle, H, provided with notches p q, severally near its ends, as set 60 forth, combined with the car F, provided with two automatic latches, r s, severally near its upper and lower ends, and riding-plates u u' v v', substantially as set forth.

11. A shutter-operating shuttle, H, provided 65 with notches p q, severally near to its ends, as set forth, combined with the car F, provided with two automatic latches, r s, severally near its upper and lower ends, and controlling devices to cause said latches to engage and disengage said notches at the proper times, where- 70 by a short shuttle may be employed.

CASS CHAPMAN.
